Fig. 4.

FIG. 5

FIG. 1 is a top plan view of a flow control valve chamber for concrete pumps or the like showing my new design.

FIG. 2 is a bottom plan view of the flow control valve chamber for concrete pumps or the like as illustrated in FIG. 1.

FIG. 3 is a left hand end elevational view of the flow control valve chamber for concrete pumps or the like as illustrated in FIG. 1.

FIG. 4 is a right hand end elevational view of the flow control valve chamber for concrete pumps or the like as illustrated in FIG. 1.

FIG. 5 is a side elevational view of the flow control valve chamber for concrete pumps or the like as illustrated in FIG. 1.

The side of the flow control valve chamber for concrete

pumps or the like opposite to the side illustrated in FIG. 5 is identical to that illustrated.

I claim:

The ornamental design for a flow control valve chamber for concrete pumps or the like, as shown and described.
